Inventor:

Oscar Finch.

United States Patent Office.

OSCAR FINCH, OF OWE GO, NEW YORK.

Letters Patent No. 68,864, dated September 17, 1867.

IMPROVED TRACE-BUCKLE.

The Schedule referred to in these Letters Patent and making part of the same.

TO ALL WHOM IT MAY CONCERN:

Be it known that I, OSCAR FINCH, of Owego, in the county of Tioga, and State of New York, have invented a new and improved Trace-Buckle; and I do hereby declare that the following is a full and exact description thereof, reference being had to the accompanying drawings, and letters of reference marked thereon.

My improved buckle is provided with two front bars *c c*, and side-strap loop *b*, and a curved lever, *f*, pressing the trace outward against the cross-bars *c c*, thereby relieving the tongue *i* from any strain, thus preventing the trace from breaking or splitting; also bending the trace outward, and preventing it from rubbing against the horse.

I claim, as a new article of manufacture—

A trace-buckle, with a curved lever pressing the trace outward against two cross-bars, thereby preventing the trace from tearing or breaking, and preventing injury to the horse, as set forth.

OSCAR FINCH.
